CLAIM

The ornamental design for a bipedal robot, as shown and described.

DESCRIPTION

FIG. 1 is a perspective view of the bipedal robot.

FIG. 2 is a rear view of the robot.

FIG. 3 is a front view of the robot.

FIG. 4 is a top view of the robot.

FIG. 5 is a bottom view of the robot; and,

FIG. 6 is a left side view of the robot.
